COMBINED GARBAGE CAN CABINET AND UTILITY RECEPTACLE

Abraham N. Block, Miami, Fla., assignor to Everglades
Industries, Inc., Miami, Fla., a corporation of Florida

Application April 24, 1957, Serial No. 45,877

Term of patent 14 years

(Cl. D33—19)

Fig. 1.

Fig. 2.

Fig. 3.

Fig. 4.

Figure 1 is a front elevation of a combined garbage can cabinet and utility receptacle, showing my new design, Figure 2 is a side elevation thereof,

Figure 3 is a vertical section taken substantially on line 3—3 of Figure 2 and,

Figure 4 is a top plan view thereof.

The back of the cabinet is of conventional configuration. I claim:

The ornamental design for a combined garbage can cabinet and utility receptacle, as shown and described.
